UNITED STATES PATENT OFFICE.

WILLIAM FLETCHER HUNTER, OF ARCATA, CALIFORNIA, ASSIGNOR OF ONE-HALF TO
LOUIS C. EVERDING, OF ARCATA, CALIFORNIA.

TOOL.

1,410,184.

Specification of Letters Patent. Patented Mar. 21, 1922.

Application filed July 2, 1920. Serial No. 393,508.

To all whom it may concern:

Be it known that I, WILLIAM FLETCHER HUNTER, a citizen of the United States, residing at Arcata, in the county of Humboldt and State of California, have invented a new and useful Tool, of which the following is a specification.

The present invention relates to vises, and more particularly to portable vises to be employed in wood working.

It is therefore the primary object of the invention to provide a vise of this character having means to permit the same to be readily and easily clamped to any stationary object, such as the studding or rafters of a building, in a manner to secure the vise against displacement.

A further object of the invention is to provide novel means associated with one end of the vise to adapt the vise for various usages.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 illustrates a plan view of a vise constructed in accordance with the present invention, showing the movable jaw removed.

Figure 2 illustrates a side elevational view of the same.

Figure 3 illustrates a front elevational view of one of the securing members.

Figure 4 illustrates a fragmental side elevational view of a saw set attachment.

Figure 5 illustrates a plan view of the same; and

Figure 6 illustrates an end view.

Referring to the drawings in detail, the reference character 5 designates the body or supporting arm of the vise, which is provided with the integral arms 6 and 7, the arm 6 being provided with a serrated surface, to bite into the support to which the device is secured.

The opposed arm 7, is provided with a

suitable threaded opening to accommodate the threaded shank 9 of the movable jaw 55 10 which is also provided with a serrated surface 11 to prevent movement of the body portion when the vise is in operation, and as shown, this shank 9 is provided with the wings 12 by means of which the movable jaw 60 10 may move into clamping engagement with the arm 6.

Formed in one end of the body 5, is an opening 13 adapted to receive the threaded shank 14 of the head 15 that has provided in 65 one surface thereof, a plurality of intersecting notches 16, for purposes to be herein-after more fully described, there being provided a winged nut 17 operating on the shank 14 by means of which the head 15 may 70 be secured within the opening 13. Intersecting the opening 13, is a transversely extending opening 13' adapted to accommodate the shank 14, so that the head 15 may be disposed at right angles to the position as indicated by Figure 1 of the drawings.

As shown, by Figure 1 of the drawings, the clamp 18 is supported by the vise, and which clamp is formed with a pair of spaced 80 ears 19 and 20, which grasp the head 21 formed on one end of the shank 22 that is provided with ribs 23, adapted to be positioned in the notches 16, of the head 15, so that rotary movement between the heads 15 85 and 21 is prevented.

In operation, the shank 22 is adapted to be positioned in the opening 24 formed in the head 15, the coiled spring 25 which encircles a portion of the shank 22, and which is held 90 thereon by means of the cotter pin 26, being for the purpose of urging the ribs 23 into predetermined notches 16 of the head 15.

From the foregoing it will be obvious that by moving the shank against the tension of the spring 25, the clamp 18 and its shank may be adjusted to unlimited angles. In order that the ears 19 and 20 will be clamped to the head 21, the bolt 27 is provided, on which bolt operates the nut 28.

As shown by Figures 4, 5 and 6 of the drawings, a novel form of saw supporting vise is provided, which includes a pair of relatively long opposed jaws 29 and 30 having right angled ends 31 and 32 which are 105 hingedly connected as by means of the pivot

pin 33 extending through suitable registering openings in the ears 35, there being provided a spring member 36 including the pin 33, the ends thereof being anchored in openings formed in the right angled ends 31 to normally urge the upper portions of the right angled ends together.

The right angled ends 31 and 32 are cut away as at 37, and are provided with inclined walls 38 adapted to cooperate with the wedge-shaped portion of the lever 39 which is pivotally supported between the ends 31 and 32, so that when lever 39 is moved upward it forces the upper extremities of right angled ends 31 and 32 apart, bringing the lower portions or jaws 29 and 30 together to clamp a saw or similar tool.

A laterally extending arm 40, forms a part of the jaw 29, and this arm 40, carries 20 the shank 41, extending downwardly therefrom, which shank is threaded as at 42 to receive the nut 43 for securing the shank 41 in the opening 24 of the head 15, when the device is to be employed as a saw supporting 25 vise.

In view of the foregoing description, a further detail description of the operation of the device is believed unnecessary.

What I claim is:—

In a device of the character described, a 30 body portion having clamping means at one end thereof, and openings at the other end, a shank adjustable in said openings, and a wing nut for holding said shank in position, a notched head on afore mentioned shank 35 and having a central opening therein, a shank positioned in said central opening, a ribbed head on said shank, a spring for holding said ribbed head in contact with afore mentioned notched head, and clamp- 40 ing means pivotally mounted on afore mentioned ribbed head.

In testimony that I claim the foregoing as my own, I have hereto affixed my signature in the presence of two witnesses.

WILLIAM FLETCHER HUNTER.
